TUMBLER LOCK

Harry F. George, Chicago, Ill.

Application April 9, 1947, Serial No. 740,390

14 Claims. (Cl. 70—363)

1

This invention relates to tumbler locks and more particularly to such locks in which metallic springs are eliminated.

In tumbler locks as known prior to the present invention, metallic springs have been used for normally urging the tumblers into locked position away from the parting plane. Such springs have been subject to breakage because of their necessary small size, which breakage when occurring would destroy the usefulness of the lock. Metal springs are also liable to become distorted, corroded or otherwise incapacitated, and for these as well as other reasons unable to successfully perform their intended purpose. In the present invention, metal springs are eliminated without in any way lessening the efficiency and ease of operation of the lock.

Among the objects of my invention are: to provide a novel and improved tumbler lock; to provide a tumbler lock in which metal springs for the tumblers are eliminated; to provide non-metallic resilient means for urging the tumblers forward and which means is considerably larger in cross-section than the cross-sectional area of the hole in which the respective tumbler slides; to provide a resilient block for yieldably receiving the thrust of the tumblers when forced by the key from distended position into position in the parting plane during the unlocking operation; to provide a block of rubber or the like, of a size to yieldably receive the thrust of all of the tumblers; and such further objects, advantages and capabilities, inherently possessed by my invention, as will later more fully appear.

My invention further resides in the combination, construction and arrangement of parts illustrated in the accompanying drawings, and while I have shown therein preferred embodiments, I wish it understood that the same are susceptible of modification and change without departing from the spirit of my invention.

In the drawings:

Fig. 1 is a perspective view of a tumber lock embodying my invention.

Fig. 2 is a perspective view of the key adapted to be inserted into the lock of Fig. 1 for operating the same.

Fig. 3 is a longitudinal section through the median plane of my lock with the plug in elevation, and showing the lock in locked position.

Fig. 4 is an end elevation looking toward the left hand side of Fig. 1.

Fig. 5 is a view similar to Fig. 3, but showing the key in position after having moved the tumbler pins to unlocking position.

Fig. 6 is an end elevation looking toward the right hand side of Fig. 1.

Fig. 7 is a longitudinal section through a median plane at right angles to the plane of the section of Fig. 5.

2

Fig. 8 is a transverse section on the line 8—8 of Fig. 7.

Fig. 9 is a transverse section on the line 9—9 of Fig. 7.

Fig. 10 is a perspective view of the rubber block detached from the other parts.

In the form shown in Figs. 1 to 10 inclusive of the drawings, my invention comprises a shell 1 adapted to be fixedly secured in any desired object to be releasably locked in position. As seen in Figs. 3 and 4, in this form of my invention the shell 1 is formed with an interior cylindrical opening 2, the key end of the shell having an inwardly extending annular offset 3 which joins with a second annular offset 4, the latter of which in effect constitutes a flange. The flange 4 is circular around its interior except that it is provided with a radial notch 5 to receive a lug 6 on the key 7. Fixedly mounted to the interior wall of the shell 1 is a tumbler pin cylinder 8 having a plurality of circumferentially spaced openings 9 for slidably receiving tumbler pins 10 of different lengths as is common in tumbler lock practice. Cylinder 8 is fixed to shell 1 in any suitable manner, as for example, by a pin 11 passing through and fixed in both of the shell and the cylinder 8, or by welding, brazing or in any other manner sufficient to fix cylinder 8 to shell 1. Cylinder 8 is formed with a circular central opening to rotatably receive the plug 12, which plug is rotated within the shell upon rotation of the key 7.

Positioned between the fixed cylinder 8 and shoulder 3 is a cylinder 13 provided with circumferentially spaced holes for receiving the longitudinally slid able tumbler pins 14. Pins 14, when the tumbler lock is in locked position, will be in longitudinal alignment with the tumbler pins 10. Tumbler pins 10 will also be of different lengths as is common in tumbler lock practice. Tumbler pin cylinder 13 is fixed to the plug 12 in any desired manner as by the integral spline 15 shown in Figs. 7 and 8. Any other suitable means for fixing cylinder 13 to plug 12 may be availed of as desired. Cylinder 13 is rotatable with relation to the shell 1 so that as the plug is rotated cylinder 13 will rotate with the plug within the shell. As will be understood a complementary groove or keyway will be formed in the plug to receive the spline 15, which keyway 16 extends to the key end of the plug to facilitate assembly of parts.

Fixed upon the right hand end of plug 12, as viewed in Figs. 1, 3, 5 and 7, is a cam plate 17, which cam plate has fixed thereto a crank pin 18, so that when the plug 12 is rotated, cam plate 17 and crank pin 18 move therewith. A portion of the cam plate 17 is radially extended at 19 so that its shoulders 20 and 21 will respectively strike the ends 22 and 23 of the extension 24

of the shell so as to limit the amount of rotation of the plug and cam plate in either direction of rotation. To further guarantee non-slipping of the cam plate 17 with relation to plug 12 the plug at its end portion is flattened at 25 on its two sides to fit within a similarly shaped opening in the cam plate to give a non-circular connection between these parts so as to insure that the cam plate will always be rotated when the plug is rotated.

Positioned between the inner face of cam plate 17 and the right hand end of cylinder 8, as viewed in Fig. 3, is a block 26 of resilient material such as rubber or the like. This rubber block is formed with a central opening 27 within which the plug is rotatable. Block 26 is also non-rotatably fixed in any desired manner to the inside surface of the shell 1. One method of fixing these parts together is by means of a pin 28 fixed in a hole in the shell and passing into the rubber block. As seen in Figs. 3, 5 and 7, the ends of each of the tumbler pins 10 adjacent the block 26 are formed with a head 29 to provide a somewhat larger bearing surface against block 26.

Such heads, however, could be omitted if desired, as the main requirement is that the ends of the tumbler pins 10 when the lock is being unlocked returnably indent, or are forced into the material of the rubber block. The resilience of this block will return the tumbler pins to their initial locked position, shown in Fig. 3, when the pressure of the key is relieved from the ends of the tumbler pins 14. As seen in Fig. 10, the rubber block in the form of my invention shown in Figs. 1 to 10, is in the form of a disk with substantial thickness so as to give the necessary amount of material for the required advancing and retarding of the tumbler pins. This disk or block is formed in the desired location around its circumference with an opening 30 to receive the pin 28 earlier referred to herein. Also this plug is formed at preferably equal distances around its circumference with radial slots 31 extending partway through the thickness of the rubber block. This provides a plurality of separate portions 32 to increase the efficiency of the action of the rubber block when one or more of the tumbler pins is being pressed thereto with a resiliency that will return the pin or pins when the key is removed. In other words, these separate portions 32 enable these portions of the rubber block to act independently without exerting a pull on the portions of the rubber block on each side of said portions 32.

As seen in Fig. 7, the key adjacent its forward end is formed with a more or less elongated rib 33 which enters the keyway 16 in the plug when the key is inserted into the lock. The key 7 is formed with bittings 34 which is common in tumbler lock practice which bittings will vary with various locks. As seen in Fig. 3, when the lock is in locked condition and the key removed, the outer ends of the tumbler pins 14 will raise against the side edges of flange 4 at spaced apart circumferential points in such manner that approximately half of each of tumblers 14 will be inside of the circle of smallest diameter of flange 4 and the other half of said tumbler pins will be resting against the inner face of flange 4. The tumbled pins are held in that position by the resiliency of the rubber block 26. It will also be understood that the length of the tumbler pins of the lock, and the lengths of the bittings 34 will be such that when the key is pushed home the abutting ends of tumbler pins 10 and 14 will be

positioned in line with the parting plane between the contacting faces of cylinders 8 and 13 to permit rotation of the plug.

In the operation of this form of my lock, it will be understood from the above, that when the key 7 is inserted into the annular space 35 between the adjacent ends of the plug and flange 4 with the lug 6 entering notch 5, the rear ends of the bittings will, at the proper moment, strike the rear ends of the tumbler pins 14 and push the same inwardly to bring their opposite ends into the parting plane. This movement will continue until the end of the key strikes the end of the cylinder 13 at which time the opposite ends of tumbler pins 14 will all fall in the parting plane, having in the meantime pushed the inner ends of tumbler pins 10 into the same plane. This permits rotation of the plug 12 and unlatching of the latch with which the lock is conventionally connected. This inward movement of the tumbler pins forces the heads 29 of tumbler pins 10 into the material of the rubber block 26 where they are held by abutment of the key lug 6 against the inner face of shell flange 4 until the key is again reversed to position for removal. This compression of the material of rubber block 26 normally urges the tumbler pin to move in an outward direction which, when the key is returned to removing position, will again move the tumbler pins into locked position as shown in Fig. 3. In each of Figs. 5 and 7, the key is shown as pushed into position to unlock the tumblers to permit the plug 12 and the cam plate 17 to be rotated together. As seen in Fig. 9, one set of tumbler pin openings is omitted to provide for the notches 5 and 16 for the key.

It is thus seen that I have provided a novel tumbler lock in which the use of metallic springs are eliminated, thus obviating rust of such springs, breakage of the same, or other spring failures. My new form of lock also greatly simplifies tumbler locks, and enables them to be much more economically produced without losing any of the efficiency of such locks. My present invention also eliminates the need of dismantling the lock in order to repair a broken metallic spring, which broken spring would destroy the usefulness of the lock. While I have referred to block 26 as being rubber, any other suitable non-metallic material may be used which possesses the general resiliency of rubber and which will return the tumbler pins to locked position when the key is removed.

Having described my invention, I claim:

1. In a tumbler lock, a shell, a plug, a first tumbler cylinder fixed to said plug, a second tumbler cylinder fixed to said shell, each of said cylinders having a plurality of holes extending therethrough parallel to the axis of said cylinders, tumblers in said holes, and a block of yieldable resilient material mounted in back of said second tumbler cylinder for yieldably biasing the tumblers during unlocking of the lock.

2. A tumbler lock as claimed in claim 1, in which said block is formed of rubber.

3. A tumbler lock as claimed in claim 2, in which said rubber block is of an external diameter approximately that of the interior diameter of the adjacent portion of said shell.

4. A tumbler lock comprising, a shell, a plug within said shell and having fixed at one end a cam plate for operating locking means, a pair of tumbler cylinders arranged end to end between the shell and the plug, the contacting ends of said

cylinders, falling in a common parting plane, tumblers in each of said cylinders slidably extending therethrough parallel to the axis of said cylinders, one of said cylinders being fixed to the shell and the other being fixed to the plug, and a resilient block positioned in the shell between the cam plate and the cylinder which is fixed to the shell for yieldably biasing the tumblers during unlocking of the lock.

5. A tumbler lock comprising, a shell, a plug in said shell adapted to be rotated therein by a key, a plurality of tumbler cylinders between said shell and plug, one of said cylinders being fixed to the shell and another one of said cylinders being fixed to the plug, tumblers longitudinally slidably in said cylinders and extending therethrough parallel to the axis of said cylinders, a resilient block fixed to said shell and within which the plug is rotatable, said block being mounted in back of the end of the cylinder which is fixed to the shell for yieldably biasing the tumblers, whereby when a key is inserted into the lock said tumblers will be moved longitudinally and the ends of some of the tumblers will be returnably indented into the material of the resilient block.

6. A tumbler lock comprising, a shell, a rotatable plug, a pair of tumbler cylinders one fixed to the shell and the other fixed to the plug, tumblers slidably mounted in said cylinders and extending therethrough parallel to the axis of said cylinders, and a rubber block mounted in back of the end of one of said cylinders to be resiliently indented by the adjacent ends of the tumblers when a key is pushed into the lock, said block yieldably biasing the tumblers during unlocking of the lock.

7. A tumbler lock as claimed in claim 6, in which the rubber block is formed with an axial opening to rotatably receive said plug, and is fixed to said shell.

8. A tumbler lock as claimed in claim 6, in which the rubber block is formed with a plurality of slits extending longitudinally part way into the block, to provide a plurality of independent thrust-receiving-ports one for each set of aligned tumblers.

9. A tumbler lock as claimed in claim 6, in which the tumblers are of varying length and are pushed endwise by a key during the unlocking operation at which time the inner ends of the tumblers are pushed different distances into the rubber block, and when the key is removed the resiliency of the block will return the tumblers to locked position.

10. In a tumbler lock, a shell, a rotatable plug having a cam plate fixed on one end, a tumbler cylinder fixed to said shell in spaced relation to the cam plate, a second tumbler cylinder fixed to said plug in rotatable contact with the first mentioned tumbler cylinder, sets of tumbler pins slidably mounted in said tumbler cylinders and extending therethrough parallel to the axis of said plug and adapted to be moved by a key to unlocked position, a cylindrical rubber block fixed to said shell in the space between the cam plate and the first mentioned tumbler cylinder and contacting the adjacent ends of the tumbler pins in said first mentioned tumbler cylinder, said rubber block in its end nearest said first mentioned tumbler cylinder having a plurality of radial slots extending inwardly a portion of the length of the block to form individual portions each receiving the adjacent ends of the

tumbler pins in said first mentioned tumbler cylinder, the ends of the tumbler pins contacting said individual portions of the rubber block each having an enlarged head to be returnably indented into the material of said individual portions of the rubber block, whereby said individual portions will act independently of each other without exerting a pull on adjacent individual portions when the tumbler pins are moved by a key to unlocked position, and return the pins to normal position when the force moving the pins is removed.

11. In a tumbler lock, a shell, a plug, a first tumbler cylinder fixed to said plug, a second tumbler cylinder fixed to said shell, each of said cylinders having a plurality of holes, tumblers in said holes extending therethrough parallel to the axis of said cylinders, a block of yieldable resilient material mounted in back of said second tumbler cylinder for yieldably biasing the tumblers during unlocking of the lock, said block being formed of rubber, and each of the tumblers abutting the block being formed with a head at all times contacting said block.

12. In a tumbler lock, a shell, a plug, a first tumbler cylinder fixed to said plug, a second tumbler cylinder fixed to said shell, each of said cylinders having a plurality of holes, tumblers in said holes extending therethrough parallel to the axis of said cylinders, a block of yieldable resilient material mounted in back of said second tumbler cylinder for yieldably biasing the tumblers during unlocking of the lock, said block being formed of rubber and being non-rotatably fixed to said shell.

13. A tumbler lock as claimed in claim 12, in which said rubber block is formed with a longitudinal central hole within which said plug is rotatably mounted.

14. In a tumbler lock, a shell, a plug, a first tumbler cylinder fixed to said plug, a second tumbler cylinder fixed to said shell, each of said cylinders having a plurality of holes, tumblers in said holes extending therethrough parallel to the axis of said cylinders, and a block of rubber mounted in back of said second tumbler cylinder for yieldably biasing the tumblers during unlocking of the lock, said rubber block being formed with a longitudinal central hole within which said plug is rotatably mounted, and said rubber block being formed with a plurality of radial slits to provide a plurality of laterally separate cushions one for each tumbler in said second tumbler cylinder.
